OTHER PUBLICATIONS

United States Patent Office Action for U.S. Appl. No. 29/599,972 dated Jun. 6, 2018 (10 pages).

Primary Examiner — George D. Kirschbaum*Assistant Examiner* — Clese Moore, Jr.(74) *Attorney, Agent, or Firm* — Michael Best & Friedrich LLP(57) **CLAIM**

The ornamental design for an electric drifter fender, as shown and described.

DESCRIPTION

FIG. 1 is a top perspective view of an electric drifter fender, showing our new design;

FIG. 2 is a right side view of FIG. 1;

FIG. 3 is a left side view of FIG. 1;

FIG. 4 is a front view of FIG. 1;

FIG. 5 is a rear view of FIG. 1;

FIG. 6 is a top view of FIG. 1; and,

FIG. 7 is a bottom view of FIG. 1.

The broken lines shown illustrate portions of the electric drifter fender that form no part of the claimed design.
